US00D951464S

(12) **United States Design Patent** (10) Patent No.: **US D951,464 S**
(45) Date of Patent: **** May 10, 2022**

(54) **THERMAL PACK**(71) Applicant: **Biofreeze IP Holdings, LLC**, Akron, OH (US)(72) Inventor: **Carol Baltazar**, Glenwood, MD (US)(73) Assignee: **TheraPearl, LLC**, Columbia, MD (US)(***) Term: **15 Years**(21) Appl. No.: **29/745,541**(22) Filed: **Aug. 6, 2020****Related U.S. Application Data**

(60) Continuation-in-part of application No. 29/740,213, filed on Jul. 1, 2020, which is a continuation-in-part of application No. 29/647,787, filed on May 15, 2018, now Pat. No. Des. 908,902, which is a continuation-in-part of application No. 29/558,747, filed on Mar. 21, 2016, now abandoned, which is a continuation of application No. 29/498,780, filed on Aug. 7, 2014, now Pat. No. Des. 787,080, which is a continuation-in-part of application No. 29/429,143, filed on Aug. 7, 2012, now abandoned, which is a division of application No. 12/794,576, filed on Jun. 4, 2010, now abandoned.

(57) **CLAIM**

The ornamental design for a thermal pack, as substantially shown and described.

DESCRIPTION

FIG. 1 is a front elevation view of a thermal pack showing the new design.

FIG. 2 is a rear elevation view thereof.

FIG. 3 is a top elevation view thereof.

FIG. 4 is a bottom elevation view thereof.

FIG. 5 is a right-side elevation view thereof.

FIG. 6 is a left-side elevation view thereof; and,

FIG. 7 is a perspective view thereof.

The spheres or beads illustrated in the drawings are drawn to appear transparent or semi-transparent. The contour lines depicted in the drawings depict the surface and contours of the clear or transparent flexible outer pack shell, which encloses the illustrated spheres or beads. Structure illustrated in broken lines is not otherwise part of the claimed design.
